UNITED STATES PATENT OFFICE.

ZACHARIAH FIELDER, OF HANNIBAL, MISSOURI.

MACHINE FOR MOLDING CEMENT BLOCKS.

SPECIFICATION forming part of Letters Patent No. 773,137, dated October 25, 1904.

Application filed February 6, 1904. Serial No. 192,470. (No model.)

To all whom it may concern:

Be it known that I, ZACHARIAH FIELDER, a citizen of the United States, residing at Hannibal, in the county of Marion and State of Missouri, have invented a Portable Press or Machine for Molding Cement Blocks, of which the following is a specification.

This invention relates to an improved press or machine for molding cement building-blocks, and has for its object to provide a simple, inexpensive, and efficient device of this character mounted to travel on a section of track between the rails of which are placed the mold-boxes, so that by moving the press backward or forward said press may be moved to a position directly over any particular set of mold-boxes.

The invention consists in the construction and novel combination and arrangement of parts hereinafter fully described, illustrated in the accompanying drawings, and pointed out in the claims hereto appended, it being understood that various changes in form, proportion, and minor details of construction may be resorted to without departing from the principle or sacrificing any of the advantages of this invention.

In the accompanying drawings, forming a part of this specification, Figure 1 is a side elevation of a portable press constructed in accordance with my invention. Fig. 2 is an end view of the same. Fig. 3 is a top plan view of a portion of the frame.

Similar numerals of reference indicate corresponding parts in all the figures of the drawings.

The press comprises an open-ended frame or carriage 5, mounted for travel on a section of track 6, the rails of which are secured in any suitable manner to cross-ties 7, preferably embedded in concrete, cement, or similar material, so as to form a smooth solid road-bed, as shown.

The frame of the press, which may be formed of wood, metal, or other suitable material, consists of a pair of spaced longitudinally-disposed side beams 8, to which are bolted uprights 9, said uprights being provided with laterally-extending flanges 9', which rest on the side beams and are provided with open-

ings for the reception of bolts 10. The uprights 9 are provided with vertically-disposed coincident slots or recesses 11, which extend from the top of each upright to a point adjacent the lower edge thereof, said uprights being connected at the top by a cross-beam 12, the reduced ends 13 of which engage the slots 11 and are secured therein by bolts 14.

Slidably mounted in the slots or recesses 11 is a plunger 15, operated through the medium of a pair of depending screws 16, said screws having their smooth upper portions passing through bearing-collars 17, secured in suitable openings in the cross-beam 12. The screws 16 are each provided at one end thereof with a spur gear or pinion 18, which meshes with an intermediate gear 19, secured to a vertical stem 20, also journaled in a bearing-collar 21 on the cross-beam 12. The stem 20 is provided with a lever or sweep 22, by means of which the screws 16 are rotated to reciprocate the plunger 15.

Mounted on the road-bed at suitable intervals are tables or platforms 23, adapted to support the mold-boxes 24, said boxes being of the ordinary knockdown type and provided with the usual presser-plate 25.

In operation the mold-boxes being filled with cement or other suitable material and arranged at predetermined intervals in the road-bed the press is moved to a position directly over the first set and the sweep operated, thereby forcing the plunger downwardly in engagement with the presser-plates 25. After the first set of mold-boxes have been subjected to sufficient pressure the plunger is retracted and the press moved to the next set, the boxes of the former set being removed and the molded blocks detached to dry.

Having thus described the invention, what is claimed is—

1. The combination with a track, of a plurality of mold-boxes arranged between the rails of said track, a carriage mounted for travel on the track and comprising an open-ended frame, a plunger mounted for vertical movement on said frame, a pair of screws engaging the plunger, pinions carried by said screws, and a gear-wheel meshing with said pinions for reciprocating the plunger.

2. The combination with a track, of a platform arranged between the rails of said track, mold-boxes supported by said platform, a carriage mounted for travel on the track and comprising an open-ended frame, a reciprocating plunger carried by said frame, a pair of screws engaging the plunger, pinions carried by said screws, an intermediate gear meshing with said pinions, means for guiding said plunger, and a lever carried by the intermediate gear for rotating the same to thereby reciprocate the plunger. 35
3. The combination with a track, of a plurality of mold-boxes arranged between the rails of said track, a carriage mounted for travel on the track and comprising an open-ended frame, slotted uprights secured to the side bars of the frame, a cross-beam connecting said uprights, a plunger mounted for vertical movement in the slots of said uprights, a plurality of depending screws carried by the cross-beam and engaging the plunger, and means for rotating the screws to thereby reciprocate the plunger. 40
4. The combination with a track, of a plurality of mold-boxes arranged between the rails of said track, a carriage mounted for travel on the track and comprising an open-ended frame, a plunger mounted for vertical movement on said frame, and means for reciprocating said plunger. 45
5. The combination with a track, of a plurality of mold-boxes arranged between the rails of said track, a carriage mounted for travel on the track and comprising an open-ended frame, slotted uprights secured to the side bars of the frame, a cross-beam connecting said uprights, a plunger mounted for vertical movement in the slots of said uprights, a plurality of depending screws carried by the cross-beam and engaging the plunger, and means for rotating the screws to thereby reciprocate the plunger. 50
6. In a device of the class described, a traveling carriage comprising a pair of longitudinal beams, a pair of oppositely-disposed slotted uprights each provided with laterally-extending perforated flanges mounted on the side beams, bolts passing through the perforations in said flanges and engaging the side beams, a cross-beam connecting the upper ends of said uprights, a plunger slidably mounted in the slots of the uprights, a pair of depending screws journaled in the cross-beam and engaging the plunger, pinions carried by the screws, an intermediate gear-wheel journaled in the cross-beam and meshing with the pinions, and a lever for rotating said intermediate gear to thereby reciprocate the plunger. 55
